UNITED STATES PATENT OFFICE.

BY TELL TEMPLETON AND CHARLES J. ROELLE, OF POCATELLO, IDAHO.

COMBINED CHIMNEY COWL AND VENTILATOR.

Application filed February 10, 1925. Serial No. 8,262.

This invention relates to a combined chimney cowl and ventilator.

The object is to provide a simple and cheaply manufactured device which may be easily installed upon a chimney or stack for the purpose of superinducing an up-draft therein to cause the fire to burn freely, as in the winter time; or by a manipulation of certain parts of the device, to reverse the action of the air so that the latter may freely pass down the chimney or stack to cause the circulation of fresh air through the rooms of the building, for ventilating purposes in the summer time.

Another object is to provide a device of this character which may be easily and quickly adjusted into position to accomplish either of the above purposes, and to mount the parts, in compact form, upon revolving means so as to permit the device to turn by the action of the wind in order to receive the full force thereof, and direct the same either to cause a down-draft or an up-draft in the stack or chimney.

A final object is to provide means in such a device which will serve to exclude dust and dirt therefrom when the device is used as a ventilator, and to provide means for excluding rain water at all times.

A full and complete understanding of the invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified so long as such changes or modifications mark no material departure from the salient features of the invention, as specifically pointed out in the appended claims.

In the drawings, in which similar reference characters designate corresponding parts throughout the several figures:—

Figure 1 is a perspective view showing the improved device in position upon the chimney of a small building;

Figure 2 is an enlarged vertical, longitudinal section through the device detached from the chimney;

Figure 3 is a top plan view, partly in

horizontal section, of the subject matter of Figure 2.

Figure 4 is a rear elevation thereof.

Figure 5 is a front elevation.

Figure 6 is a detail section.

Referring more particularly to Figure 2 of the drawing, there is shown a combined draft control and ventilator embodying a horizontal, tubular body member 1, constituting a wind trunk, through which the air blowing at the top of the house or building, is adapted to pass. The trunk may be of any desired size and proportions, depending on the size and nature of the chimney or stack, and is preferably formed of some suitable, strong sheet metal to resist the force of the wind and to withstand the actions of the elements.

Each end of the wind trunk is normally open, and adjacent to one end there is suitably connected a perpendicularly disposed branch or flue 2, communicating therewith and adapted to stand upright beneath the wind trunk and to support the same in the manner to be described.

The flue 2 is preferably of the same diameter and cross-sectional shape as the wind trunk, though somewhat shorter than the same, and adjacent to the open, bottom end of the flue, there is secured an annular ring 3, exteriorly fitting the same and held thereto by rivets or otherwise. The ring is provided on its under face with an annular ball race and constitutes an element of an anti-friction device.

The lower end of the flue 2 is placed over the upper end of an extension pipe 4, which is adapted to be secured, in any desired manner, to the upper open end of a chimney 5, as shown in Figure 1 of the drawing, but where the device is to be used at the top of a tubular sheet metal stack, the showing may be taken as indicative of the latter.

The pipe 4 is provided with a complementary ring 6, suitably held in position thereon and provided with a coacting ball race, the balls 7 being interposed between the two rings in the usual manner, to permit the trunk 1 and the flue 2 to rotate freely about the vertical axis of the latter, the upper ring having a depending, peripheral flange overhanging the lower ring to exclude rain water, etc.

The lower ring may be provided with hooks 8 or the equivalent, to which are secured the upper ends of guy wires 9 to steady and brace the upper end of the pipe 5 or stack.

That end of the wind trunk closest to the flue 2 constitutes the entrance end of said trunk, and is provided with a funnel-shaped extension 10 to catch the wind, in a 10 well known manner, and the mouth of the funnel is covered with a wire screen 11 to prevent the entrance of dust, dirt and insects within the trunk.

The upper portion of the mouth of the 15 funnel is also provided with a substantially semi-circular inclined rain shed 12, suitably held thereto and formed of suitable sheet metal, while within the entrance end of the trunk and secured to the lower portion thereof, is a baffle plate 13, cut around its sides and lower portion to fit the curvature of the trunk, and provided with a marginal flange for attaching the same in position, the upper edge of the plate being formed straight 20 across or horizontal. The upper, straight edge of the baffle plate is located below the longitudinal axis of the trunk, as shown in Figure 2, and said plate also serves to cause any rain water entering the trunk 25 to flow back again, to be directed down and out by the inclined wall of the funnel.

The opposite, rear or outlet end of the trunk is equipped with a door or cover 14, having a marginal flange 15, and hinged at 30 the top to the end of said trunk, as indicated at 16, said door being adapted to be swung downwardly to close the end of the trunk, with the peripheral flange surrounding the end of the trunk so as to prevent the passage of air therethrough when desired.

Mounted on top of the wind trunk is a 45 longitudinally disposed, upstanding vane 17, formed preferably of two sheets of suitable sheet metal, the margins of one sheet being flanged over the edges of the other, as indicated at 18 in the drawings and the two sheets being further secured by rivets 19.

The trap door or cover 14 is adapted to be opened, and held open by a suitable chain 50, having one end secured to said door and passing up and over a pair of pulleys or sheaves 21 mounted on one side of the vane, the other end portion of said chain passing down adjacent to the chimney or stack, 55 and adapted to have one of the links of the same secured to a hook 22, or similar device secured, to the upper ring 3, so as to revolve with the device when the same is acted upon through the medium of the aforesaid vane.

60 A coiled spring 23 serves to pull the door or cover shut, when the said chain is released from the hook 22, the ends of said spring being connected by wires 24 to the said door and to the aforesaid hook 22 respectively.

In the use of the device as a draft control during the winter months, when it is desired to cause all the draft possible upwardly through the stack or chimney, the trap door or cover 14 is elevated into the position 70 shown in Figure 2 of the drawing, and the proper link of the chain is engaged on the hook 22, when the wind trunk is entirely open and the spring is under tension. Air entering through the funnel end of the trunk 75 is caused to pass over the baffle plate 13, and then straight through the trunk and out the open end, as indicated by the full line arrow, the passage of the air over the upper end 80 of the flue 2 causing an up-draft in the latter and consequently in the chimney, as also indicated by the full line arrow.

When the door is closed, however, and held shut by the spring, the entire volume of air or wind entering the funnel end of the trunk is caused to pass downwardly through the flue and chimney to be distributed to the rooms or building as desired; and an intermediate position of the door, when held at the desired degree of elevation 90 by the engagement of the proper link of the chain with the hook, will result in a varied degree of ventilation, as is desirable in summer time, when the chimney is not in use as a smoke conductor. 95

From the foregoing it will be seen that a simple, cheaply manufactured, and easily installed device has been provided, to be mounted upon the top of a stack or chimney which may be readily adjusted to secure the desired amount of ventilation of a building, as in summer time, and which may also be adjusted to carry off the smoke and products of combustion from the fire or fires in winter time; the entire device being strong and durable and of compact form and mounted to adjust itself to the varying course of the wind. 100

105 What is claimed is:—

1. A combined chimney cowl and ventilator, comprising a horizontal wind trunk adapted to be rotatably mounted on a chimney, a wind vane secured to the top of the trunk and overhanging the outlet end, a flanged closure hinged to the top of the 110 trunk adjacent to the outlet end thereof adapted when closed to convert the device into a ventilator, a flexible pull element for raising said closure to open position, and a pulley mounted on said vane over which said pull element is trained, said pull element adapted to be fastened to hold the closure open, and said closure being adapted 115 to close when said pull element is released. 120

2. A combined chimney cowl and ventilator comprising, in combination, a horizontal wind trunk having an integral flue portion communicating therewith, and a wind vane above the outlet end, an anti-friction bearing between the chimney and the trunk, a 125 130

door having a peripheral flange mounted on a horizontal hinge at the outlet end of the trunk and arranged to swing outwardly and upwardly to open that end of the trunk, 5 means tending to close the door and hold it in closed position against the wind pressure, and means associated with the vane

whereby said door may be opened by an operator at a distance.

In testimony, that we claim the foregoing 10 as our own, we have hereto affixed our signatures.

Y TELL TEMPLETON.
CHARLES J. ROELLE.
